FEED RING WITH DRAIN GROOVES FOR ROTATING GRINDSTONE WOOD GRINDING MACHINES

George D. Illig, Lockport, N. Y., assignor, by mesne assignments, to Charles B. Roberts, Lockport, N. Y., as trustee

Application September 13, 1949, Serial No. 115,321

2 Claims. (Cl. 241—38)

1

This invention relates to improvements in machines for grinding wood to produce wood pulp, and more particularly to grinders of the type in which the wood is fed to the grindstone by means of a feed ring arranged eccentrically about the 5 grindstone.

One of the objects of this invention is to provide a feed ring for the wood having means of improved construction for facilitating the removing of ground wood from the machine. Another object is to provide a feed ring in which the surface of the feed ring which contacts with the wood is provided with drain grooves through which water carrying the ground wood may flow to the sides of the ring for discharge from the 15 machine. A further object is to provide a feed ring of improved construction with diagonally extending grooves therein for receiving the water and wood pulp, and from which water carrying the ground wood will be discharged by gravity 20 during the rotation of the feed ring. A further object is to provide a feed ring of this type in which the grooves are of substantially V-shape with the sides thereof extending rearwardly and outwardly with reference to the direction of 25 movement of the feed ring and terminating at the side edges of the feed ring.

Other objects and advantages will be apparent from the following description of one embodiment of the invention and the novel features 30 will be particularly pointed out hereinafter in connection with the appended claims.

In the accompanying drawings:

Fig. 1 is an end elevation, partly in section, of a wood grinding machine provided with a feed 35 ring embodying this invention.

Fig. 2 is a development of a portion of the inner surface of the feed ring along section line 2—2, Fig. 1.

Fig. 3 is a fragmentary transverse sectional 40 elevation of the lower part of the feed ring and the discharge troughs for the wood, the section being taken approximately on line 3—3, Fig. 1.

The wood grinding machine may be constructed approximately as shown in the Roberts Patent No. 2,282,887 of May 12, 1942 and includes an outer housing 5, a rotary grindstone 6 which may be rotably mounted in any desired manner on the housing 5, and a feed ring 7 which is also rotatable within the housing, and which is arranged in eccentric relation to the grindstone in such manner that a portion of the feed ring extends into close proximity to the grindstone 6. This arrangement results in the formation of 45 a pocket 8 for the wood to be ground. The grinding machine also includes a suitable chute, guide or hopper 9 of any desired construction into which wood may be fed from an end of the machine and deposited in the pocket 8. The 50

2

feed ring may be provided with the usual teeth or projections 10 on the inner surface thereof which engage the wood for feeding the same to the grindstone.

The feed ring may be rotated to feed the wood to the grindstone in any suitable or desired manner, and in the construction illustrated by way of example, the feed ring is provided on the outer surface thereof with a worm gear 12 suitably secured to the feed ring and having teeth with which a worm 14 engages, the worm being driven by means of a shaft 15 from any suitable source of power, as is well understood to those skilled in this art. The worm gear may be built in sections provided on their inner surfaces with tongues 17, see Fig. 3, which fit between a pair of outwardly extending projections 18 on the feed ring and pins or bolts 19 may be provided which extend through the flanges 17 and 18 for securing the worm gear on the outer surface of the feed ring. Any other means for rotating the feed ring may be provided, and the rate of rotation of the feed ring may be controlled to vary the pressure of the wood on the grindstone to produce ground wood of the type or quality desired, as is understood by those skilled in this art.

The outer surface of the feed ring may also be provided with suitable cylindrical bearing surfaces 20, which cooperate with suitable bearings on which the feed ring is rotatably supported. These bearings may be of any suitable or desired form, and in the construction shown, a pair of bearing blocks 22 are provided as shown in Fig. 1 which have suitable bearing surfaces cooperating with the surfaces 20 of the feed ring. Any other suitable means for rotatably supporting the feed ring may be provided.

The inner surface of the feed ring is also provided with a plurality of parallel and relatively shallow grooves 25 which extend slightly below the bases of the teeth or projections 10 of the feed ring, these grooves cooperating with suitable blades or scrapers which remove thin pieces, shims or slivers of wood which adhere to the roughened or toothed portion of the inner wall of the feed ring after passing the grindstone. These shims or slivers may be reground by engaging wedge-shaped blocks 26 which cause the shims or slivers to be moved into engagement with the grindstone for reducing the same to wood pulp. Any other means for regrounding the shims or slivers may, of course, be provided, if desired.

It is important in connection with a wood grinding machine to provide means for carrying away the wood pulp or wood fibers as soon as possible after they have been ground from the wood logs supplied to the machine so that these fibers will not be reground, since the regrounding

reduces the length of the fibers, and consequently, the strength of the paper made therefrom.

I, consequently, provide means of improved construction on the inner surface of the feed ring for receiving the ground wood together with water and for carrying the ground wood to the sides of the feed ring where they will be discharged into the usual troughs 28 arranged at the sides of the feed ring as shown in Fig. 3. For this purpose, I provide the inner surface of the feed ring with grooves which terminate at their outer ends at the sides of the feed ring for discharging the ground wood into the troughs 28. These grooves 30 preferably extend diagonally with reference to the parallel grooves 25 in the feed ring. Also 15 these grooves are preferably of greater depth than the parallel grooves 25 so as to provide ample capacity for the discharge of pulp and water from the inner surface of the feed ring. The grooves 30 preferably extend from the middle portions 20 of the feed ring to the side edges thereof, and preferably these grooves are so arranged as to extend rearwardly and outwardly with reference to the direction of movement of the feed ring. If desired, the inner ends of each pair of grooves 25 may be joined at the middle portion of the feed ring, thus forming grooves of substantially V-shaped form as clearly seen in Figs. 2 and 3.

In the operation of a feed ring provided with the grooves 30, water supplied by the usual spray pipe 31 washes the ground wood from the stone and from any logs adjacent thereto into the grooves 30, and outwardly beyond the sides of the feed ring into the troughs 28. Water and ground wood entering the grooves 30 before the same reach the lowermost portion of travel of the feed ring will be retained in the grooves out of contact with the wood to be ground. As the feed ring advances from the lowermost position to the left in Fig. 1, the grooves will assume positions in which the apexes or the inner ends of the grooves will be at higher elevations than the ends of the grooves which terminate at the sides of the feed ring, and consequently, any water and wood pulp which has collected in the grooves, and which is received in the grooves while in positions in advance of the lower portion of the path of movement of the feed ring will flow by gravity to the sides of the feed ring and be discharged into the troughs 28.

The construction described is desirable in that it effectually disposes of the ground wood in such manner as to avoid regrinding of the same. The feed ring described is of efficient and simplified construction and enables the parallel grooves 25 to act as feeders of the water and wood pulp to the deeper diagonal grooves 30, since any water carrying wood pulp will flow into the drainage grooves 30 during the rotation of the feed ring. Furthermore, if the diagonal drainage grooves become filled with water and pulp before they reach the lower part of the path of rotation of the feed ring, excess water and wood pulp will overflow the upper drainage grooves into the parallel grooves 25 and will in turn be discharged from the parallel grooves into lower drainage grooves of the feed ring for discharge into the troughs 28.

Because of the diagonal relation of the drainage grooves relatively to the parallel grooves 25, the drainage grooves will not interfere with the operation in the parallel grooves of the usual knives or scrapers for removing shims or slivers from the feed ring.

It will be understood that various changes in the details, materials, and arrangements of parts

which have been herein described and illustrated in order to explain the nature of the invention, may be made by those skilled in the art within the principle and scope of the invention, as expressed in the appended claims.

I claim as my invention:

1. In a wood grinding machine including a rotary grindstone, a feed ring arranged eccentrically about said grindstone with a portion of the inner surface in close proximity to the outer surface of said grindstone and rotatable to feed wood against the surface of the grindstone, means for supplying water to the portion of the grindstone contacted with the wood, teeth on the inner surface of said feed ring which engage the wood for moving the same toward said grindstone, and a plurality of shallow grooves in the inner surface of said feed ring arranged in parallel relation to the side edges of the feed ring and spaced from each other for cooperation with means for removing wood adhering to portions of said ring after passing said grindstone, that improvement which includes a plurality of drainage grooves in the inner surface of said feed ring and deeper than said first mentioned grooves and extending in angular relation thereto, and which receive water and ground wood and which terminate at the outer edges of said ring for discharging ground wood and water therefrom, said grooves extending from the middle portion of said ring to the edge portions thereof.

2. In a wood grinding machine of the type having a rapidly rotating grindstone, a feed ring extending eccentrically about said grindstone and provided on its inner peripheral face with teeth extending parallel to the axis of said feed ring, said feed ring being mounted for rotation at a speed much less than that of the grindstone and in the same direction of rotation of said grindstone, that improvement in which said ring is solid between the inner and outer peripheral surfaces thereof and has on its inner peripheral face a plurality of relatively shallow open-faced channels extending into the inner face of said feed ring and extending generally crosswise with respect to said feed ring and opening through the ends of said ring, said channels extending in depth below the base of the teeth and across the teeth and intersecting said teeth, and a spray device within said ring at the side of said stone toward which the teeth on the ring move in the rotation of the ring, for delivering a liquid to said stone to release fibers from said stone and from the wood which is being ground and flush the same into said channels for movement toward opposite ends of said ring for discharge from said ring at said ends thereof, said channels running from approximately midlength of the ring to the ends of the ring and having their outer ends trailing with respect to the direction of rotation of said ring.

GEORGE D. ILLIG.
